UNITED STATES PATENT OFFICE.

CHRISTOPHER L. STANGE, OF ST. LOUIS, MISSOURI, ASSIGNOR TO THE GRAND COUNCIL OF THE ORDER OF DE MOLAY, OF ST. LOUIS, MISSOURI.

DESIGN FOR A BADGE OR SIMILAR ARTICLE OF JEWELRY.

Application filed June 26, 1926. Serial No. 18,192. Term of patent 14 years.

To all whom it may concern:

Be it known that I, CHRISTOPHER L. STANGE, a citizen of the United States, and a resident of the city of St. Louis, State of Missouri, have invented a new, original, and ornamental Design for Badge or Similar Article of Jewelry, of which the following is a specification, reference being had to the accompanying drawing, forming part thereof.

In said drawing Fig. 1 is a front view of a badge or similar article of jewelry embodying my invention; and

Fig. 2 is a side view thereof.

I claim:

The ornamental design for a badge or similar article of jewelry, as shown.

CHRISTOPHER L. STANGE.
